Westinghouse Electric Corporation, East Pitts-
burgh, Pa. a corporation of Pennsylvania

Application March 11, 1944, Serial No. 526,017

10 Claims. (Cl. 200—82)

1

This invention relates to circuit breakers and, more particularly, to circuit breaker operating mechanisms of the pneumatic type.

Circuit breakers for electrical power systems are desired which operate at very high speeds and in which the motion of the parts can be quickly reversed, in order to obtain quick interruption and also quick reclosing of the electrical circuit. When an operating mechanism of the pneumatic type is employed for operating the circuit breaker, back fluid pressure in the operating cylinder tends to retard the speed of the opening stroke of the piston. Dump valves have been employed for opening main exhaust ports to quickly exhaust the back fluid pressure for a portion of the opening stroke of the piston on pneumatic trip-free operations. That is, when the breaker is closed in on a fault and it is necessary to quickly exhaust the closing air from the cylinder to permit high-speed opening of the breaker. After the main exhaust port is closed during the opening stroke, the fluid trapped back of the piston retards the speed of the opening stroke of the mechanism. The main dump valve on exhaust valve does not operate on normal opening operations, and the fluid, at atmosphere pressure, would be compressed during the opening stroke, thus retarding the opening movement of the breaker mechanism. This trapped fluid pressure is usually exhausted through the inlet valve which admits fluid pressure to the cylinder. In modern fluid pressure operated circuit breakers, the force required for normal closing operations is substantially less during the first portion of the closing stroke than during the final portion of the closing stroke when the heavy contact load is being overcome. For this reason it has heretofore been the practice to provide means for restricting the inlet passage to admit the minimum fluid pressure required for normal closing operations. Such restricted passages do not provide adequate and sufficiently rapid exhaust flow of the trapped fluid pressure. This results in undesirably retarding the speed of the opening operation of the breaker.

An object of the present invention is the provision of a circuit breaker with an improved operating mechanism of the pneumatic type capable of effecting high-speed operation of the circuit breaker and quick reversal of the moving parts.

Another object of the invention is the provision of a circuit breaker embodying an operating mechanism of the pneumatic type operable to produce normal closing and quick re-

2

closing of the breaker with rapid reversal of the switching movement of the breaker, the mechanism having an automatically operable valve for reducing the air pressure applied to the piston on normal closing operations and for causing full air pressure to be applied to the piston on quick reclosing operations, and having a bypass around the automatic valve for quickly exhausting the air pressure back of the piston on opening operations.

Another object of the invention is the provision of a circuit breaker operating mechanism of the pneumatic type with an improved quick-acting inlet and exhaust valve device for admitting fluid to the operating cylinder and also for rapidly and fully venting the cylinder to atmosphere to permit high-speed operation and quick reversal of the breaker operating mechanism.

Another object of the invention is the provision of a circuit breaker with an improved operating mechanism of the pneumatic type capable of effecting high-speed opening and quick reclosing of the circuit breaker.

The novel features that are considered characteristic of the invention are set forth in particular in the appended claims. The invention itself, however, both as to structure and operation, together with additional objects and advantages thereof, will be best understood from the following detailed description of one embodiment thereof when read in conjunction with the accompanying drawings, in which:

Figure 1 is an elevational view, partly in section, of a circuit breaker operating mechanism, the circuit breaker being shown schematically.

Fig. 2 is a vertical sectional view of the circuit breaker operating mechanism showing the valve structure.

Fig. 3 is an enlarged horizontal sectional view taken substantially on line III—III of Fig. 2 showing the inlet valve, the throttle valve and the several control passages.

The present invention in certain aspects is a further development and improvement of the invention disclosed and claimed in the copending application of James M. Cumming and Henry L. Peek, Serial No. 445,881, filed June 5, 1942, now Patent No. 2,384,801, issued September 18, 1945, and assigned to the assignee of the present invention.

Referring to Figs. 1 and 2 of the drawings, the circuit breaker operating mechanism comprises, generally, a main casting 11, an operating cylinder 15 in the casting, a piston 17 movable in the cylinder, a trip device indicated generally at 19

(Fig. 1), a control valve device 21 (Fig. 2) for admitting compressed air to the cylinder to effect closing movement of the piston 17, a valve 23 for controlling the air intake, an exhaust valve mechanism 25, and a latch mechanism indicated generally at 27 (Fig. 1).

The lower end of the cylinder 15 is closed by means of a closure member 29 suitably secured to the main casting 11, the upper end of the cylinder 15 being closed by a portion 33 of the casting. The piston 17 includes an upwardly extending hollow tube 35 which slidably fits within an opening in the portion 33 of the casting 11.

The tube 35 is connected, at its upper end by means of a pivot pin 41 to a link 43, which, in turn, is connected at its upper end, by means of a pivot pin 45, to a coupling 47 secured on the lower end of a breaker operating rod 49. The operating rod 49 is connected by suitable linkage to the circuit breaker mechanism shown schematically at 59 (Fig. 1) which may be an air breaker or an oil breaker of any conventional type. The breaker mechanism is biased to open position and actuated to open the breaker contacts by means of an accelerating spring 52.

The pivot pin 45 (Fig. 2) which connects the link 43 to the coupling 47, extends beyond the sides of the coupling and is connected by means of suitable bearing members 51 to an operating lever 53 comprising a pair of spaced parallel levers. As shown in Fig. 1 the levers 53 are pivotally supported, at their right hand ends, by means of a pivot pin 55, on the upper end of a link 57 whose lower end is pivoted on a pivot pin 59 mounted in a pair of ears 61 projecting outwardly and upwardly from the main casting 11.

The left hand ends (Fig. 1) of the levers 53 are rigidly connected by means of a rod 63 and are spaced apart by a roller 65 rotatably mounted on the rod 63 between the levers. The latch mechanism 27 normally cooperates with the roller 65 to releasably restrain the breaker mechanism in closed position.

The latch mechanism 27 includes a main latch 67 pivotally supported on a pivot pin 69 mounted in projections 71 extending upwardly from the main casting 11. The main latch 67 is biased to latching position by means of a spring 73 coiled around a rod 75 and compressed between a projection 77 of the casting 11 and a washer 79 supported on the lower end of the rod 75 by a nut 81. The rod 75 extends upwardly through a guide opening in the projection 77 and is pivotally connected at its upper end by means of a pivot pin 83 to the main latch 67.

The configuration of the latching surface of the main latch 67 is such that it will not, by itself, retain the operating mechanism in closed position. An auxiliary latch 85 is provided to maintain the main latch 67 in latching position. The auxiliary latch 85 is pivoted on a pivot pin 87 supported in the projection 71 of the casting 11 and a latching projection 89 thereon is biased by means of a spring 91 into latching engagement with a tail 93 of the main latch.

The auxiliary latch 85 is provided with a horizontally extending portion 95 the free end of which is disposed directly above and in alignment with a vertically disposed trip rod 97 forming a part of the trip device 19. The trip device includes, in addition to the trip rod 97, a trip magnet comprising an E-shaped magnet core 99 supported by means of a pair of brackets 101 on the under side of a projection 103 of the casting 11, the brackets 101 being suitably secured to the

projection 103. An energizing coil 107 surrounding the center leg of the core 99 and suitably supported in the magnet frame, is provided to energize the trip magnet. A movable armature 109 secured on the lower end of the trip rod 97 cooperates with the magnet core 99 when the coil 107 is energized to thrust the trip rod upwardly to effect tripping of the breaker. The downward movement of the armature 109 and of the trip rod 97 is limited by engagement with a manual trip rod 111 vertically slidably mounted in a guide sleeve 113 threadedly secured on a horizontal projection 115 of the casting 11. The vertical movement of the manual trip rod 111 is limited by means of an annular collar (not shown) thereon engaging shoulder (also not shown) formed on the inner wall of the sleeve 113. The sleeve 113 is locked in position by means of a lock nut 117.

Upon energization of the trip device 19 the armature 109 is attracted thrusting the trip rod 97 upwardly. The trip rod, at this movement, engages the portion 95 of the auxiliary latch 85 and rocks this latch clockwise to disengage the latching projection 89 thereon from the tail 93 of the main latch 67. The upward force exerted on the operating rod 49 and the lever 53 by the breaker accelerating spring 52 overcomes the relatively weaker spring 73 and forces the main latch 67 clockwise as the lever 53 rotates clockwise about the pivot 55 to open position. As soon as the roller 65 escapes the latch 67, the spring 73 acts to restore the latch to its latching position. When this occurs the spring 91 tends to move the auxiliary latch 85 to latching engagement with the main latch. Should this occur it is obvious that the latch roller 65 could not be restored to latching engagement with the main latch 67. In order to prevent the auxiliary latch from reengaging the main latch following a tripping operation and until the mechanism is restored to full closed position a holding lever 119 is provided. The holding lever 119 comprises a U-shaped lever pivotally supported on the pivot pin 87 and having the two arms thereof rigidly joined at their free ends by a cross bar 121. A spring 123, seated in a spring seat in the casting 11 biases the cross bar 121 into contact with the latch roller 65 so that, when the lever 53 and the roller 85 move in opening direction the spring 123 causes the holding lever 119 to rotate in a clockwise direction about the pivot 87. During this movement of the holding lever a lateral extension 125 thereon engages the portion 95 of the auxiliary latch 85 and, since the spring 123 is relatively stronger than the spring 91, holds the auxiliary latch in its unlatching position until the breaker is closed.

When the trip device is operated to release the operating lever 53, the accelerating spring 52 moves the operating rod upwardly as the breaker mechanism moves to open position. Due to the connecting link 43 (Fig. 2) the piston 17 moves therewith to the top of the cylinder 15. In order that the piston 17 may move rapidly upwardly in the cylinder to provide for high-speed interruption of the circuit the dump valve mechanism indicated generally at 25 (Fig. 2) is provided and is energized simultaneously with the energization of the trip device 19 (Fig. 1). The dump valve mechanism is supported on housing 127 (Fig. 2) secured to the side of the main casting 11 by means of bolts (not shown). The housing 127 is provided with a passage 131 which is in alignment with an exhaust passage 133 in the wall of the cylinder 15. The exhaust passage 131 is normally closed by means of an electro-

magnetically operated piston valve 135 disposed for vertical movement in a cylinder 137 formed integral with the housing 127.

An electromagnet, indicated generally at 139 (Fig. 2), is provided to initiate movement of the dump valve 135 to open position. The electromagnet 139 is energized simultaneously with the trip device. The electromagnet 139 includes a U-shaped stationary core 141 of laminated magnetic material supported by means of angular brackets 143 from the lower flanged end 144 of the cylinder 137. The brackets 143 are secured on opposite sides of the lower end of the stationary core 141. Screws 145 pass through each end of each of the brackets 143, through brackets 147 secured to the upper end of the core 141 and threadedly engage tapped holes in the flanged lower end 144 of the exhaust valve cylinder 137. Spacers 149 surround the screws 145 between the brackets 147 and the cylinder 137 to properly locate the magnet core.

An energizing coil 151 mounted between insulating members 153 is suitably supported on the brackets 147. The coil 151 is provided with a suitable central opening to receive a movable core 161 of laminated magnetic material pivotally supported on a yoke 163 secured to the lower end of a piston rod 167. The upper end of the rod 167 passes loosely through the head of the valve 135, and is headed as at 169 and operatively engages the closed end of the cup-like piston valve 135.

The valve 135 and the movable core 161 are biased to the closed position by a coil spring 171 compressed between a washer 173, supported on the brackets 147, and the head of the valve 135.

As was stated previously the exhaust valve magnet 139 is energized simultaneously with the trip device 19 (Fig. 1), and when energized, attracts the movable core 161 (Fig. 2) drawing the valve 135 downwardly in the cylinder 137 to slightly open the exhaust passages 131. On trip-free operations, that is, when the breaker is closed in against a fault, the compressed air in the breaker operating cylinder above the piston 17, at the time the dump valve 135 is opened by the electromagnet 139, will push the exhaust valve down to its full open position thereby quickly dumping the air from the cylinder to permit quick reversal of the mechanism and movement of the breaker to open position. As the breaker moves to open position drawing the piston 17 upwardly in the cylinder 15, the air above the piston is quickly exhausted to the atmosphere through the relatively large passage 133-131.

As the piston 17 travels upwardly it passes the exhaust port 133 after which the air trapped above the piston is compressed to absorb the kinetic energy of the moving mass of the breaker. The trapped air is vented to the atmosphere through a passage 175 (Figs. 2 and 3) extending vertically through the upper portion 33 of the casting 11 and into an extension 177 thereof, a horizontal passage 178 connecting with the upper end of the vertical passage, horizontal passages 180, 182 and 184 to the atmosphere. The passages 182 and 184 are formed in the housing 181 of the inlet valve, the passage 184 being controlled by a valve 193 disposed therein and operated by the electromagnet 197 in a manner to be fully described later.

On normal opening operations, while the electromagnet 139 is energized with the trip device and partly opens the dump valve 135, there is no compressed air in the cylinder to move the valve

135 to full open position, consequently the valve returns to closed position upon deenergization of the electromagnet 139. During a normal opening operation the air in the cylinder above the piston is exhausted through the passage comprising the passages 175, 178, 180, 182 and 184 (Fig. 3).

The circuit breaker may be manually tripped open by energizing the electrical circuit for the trip device by means of a manually controlled switch (not shown). The circuit breaker may be tripped open mechanically in case of failure of current in the control circuit (not shown) by manually operating the trip rod 97 (Fig. 1). This is accomplished by operating a bell crank 194 (Fig. 1) pivotally supported by means of a pivot pin 195 mounted in a bracket 196 secured to the under side of the projection 115 which supports the manual trip rod 111. The bent end 188 of a pull rod 190 projects through an opening in an ear 192 of the downwardly extending arm of the bell crank 194 and is suitably retained in place by a cotter pin.

When it is desired to trip the breaker mechanically the pull rod 190 is drawn toward the left (Fig. 1) which rotates the bell crank 194 clockwise thrusting the manual trip rod and the trip rod 97 upwardly to operate the latch mechanism 27. The circuit breaker then moves to the open position, the air above the operating piston 17 being expelled to atmosphere from the cylinder through the fully open passages 175, 178, 180, 182 and 184 (Figs. 2 and 3) since the dump magnet 139 is not energized upon mechanical operation of the trip device.

In order to close the breaker 59 (Fig. 1) compressed air is admitted to the cylinder 15 above the piston 17 through the inlet passage 179-175 by operation of the inlet valve mechanism 21. The inlet valve mechanism includes the housing 181 which is securely mounted by means of bolts 183 (Fig. 3) on the side of the extension 177 of the main casting. An inlet valve 185 disposed for vertical movement within the housing 181, is biased to closed position by means of a spring 187 seated on an air inlet chamber 189 suitably secured to the bottom of the housing 181. The upper end of the spring 187 bears against the valve 185. The valve 185 is secured on a rod 191 which also carries the exhaust valve 193. When the inlet valve 185 is closed the exhaust valve 193 is open connecting the upper end of the operating cylinder 15 to the atmosphere through the previously described passage. When the inlet valve 185 is operated to open position to admit compressed air to the cylinder 15 the valve 193 is moved to close the exhaust passage 184.

The inlet valve 185 and the exhaust valve 193 are operated to open position and closed position by means of the electromagnet indicated generally at 197. The magnet 197 includes a U-shaped stationary core member 199 of laminated construction supported on a plate 201 by means of angular brackets 203 suitably secured, for instance, by welding, to the core member. The brackets 203 are secured to the plate 201 which, in turn, is secured to the top of the inlet valve housing 181 by means of screws 207. An energizing coil 209 is mounted between insulating plates 211 secured to the core member 199. The lower portion of the core member 199 is provided with a clearance opening (not shown) through which the valve stem 191 passes, and the coil

209 has a central opening (also not shown) in which is disposed a T-shaped movable core 217.

The control circuits for the trip device 19 and the inlet valve electromagnet 197 are preferably the same as the control circuits disclosed in the copending application of James M. Cumming and Richard C. Cunningham, Serial No. 410,686, filed September 13, 1941, now Patent No. 2,408,199, issued September 24, 1946, and assigned to the assignee of the present invention. The control circuits have not been shown in this case as they are not necessary for a complete understanding of the present invention. It is believed sufficient for the purpose at hand to mention that the inlet valve electromagnet may be energized in response to the operation of a manual closing control switch or automatically in response to the closing of an auxiliary switch which may be set to close at an intermediate position in the opening stroke of the breaker so as to initiate quick reclosing of the breaker. The trip device 19 is energized in response to an overload or other fault condition. For details of the control circuits reference may be had to the aforementioned copending application. As previously pointed out the exhaust valve electromagnet 193 is energized simultaneously with the trip device 19.

When the electromagnet 197 is energized, the magnet attracts the movable core 217 which thrusts the valve stem 191 downwardly closing the exhaust valve 193 and opening the inlet valve 185. The inlet air chamber 186 is connected by means of a pipe 219 (Figs. 2 and 3) to a source (not shown) of compressed air. When the inlet valve 185 (Fig. 2) is opened air under pressure is admitted through the passage 179-175 to the upper end of the operating cylinder 15 moving the piston 17 toward the bottom of the cylinder and moving the connected breaker operating mechanism to closed position.

The driving force required for normal closing operations where the closing movement is initiated from the full open position is much less during the first portion of the closing stroke than during the final portion of the closing stroke when the heavy contact load is being overcome, and is also much less than that required to quickly reverse the switching movement and automatically reclose the breaker after interruption of the circuit and before the breaker reaches full open position. The automatically operable valve 23 (Fig. 2) is effective to reduce the flow of compressed air admitted to the operating cylinder during the first part of the closing stroke on normal closing operations, but permits the full flow of air pressure to the cylinder during the final portion of the closing stroke. The valve 23 is also effective to permit full flow of compressed air during quick reclosing operations to provide additional power required to quickly reverse the movement of the breaker and quickly reclose the same.

The rate of flow of compressed air to the cylinder 15 to effect closing of the circuit breaker is controlled by the previously mentioned valve 23 and by an adjustable metering pin 221 (Fig. 3) in an auxiliary air passage. The valve 23 includes a piston type valve 223 (Figs. 2 and 3) disposed for vertical movement in a cylinder formed in the projection 177 of the main casting. The valve 223 is cup-shaped and has an operating rod 227 integral therewith and extending vertically beyond the valve through an opening in a guide bracket 229. The bracket 229, which is

suitably secured to the top of the extension 177 also serves to limit the upward or closing movement of the valve. A spring 233 disposed in the hollow valve and seated in the bottom of the valve cylinder biases the valve 223 in closing direction and moves the valve to closed position as the breaker moves to open position.

The valve 223 is restrained in open position when the breaker is closed and is adapted to be moved downwardly to open position as the breaker mechanism approaches closed position by means of a tappet 237 (Figs. 1 and 2) secured by means of bolts 239 to an angle bracket 241 which is secured by means of welding to the adjacent operating lever 53.

15 The valve 223 is shown in Fig. 2 in the open position in which an annular groove 245 on the outer periphery of the valve is in alignment with the passages 175 and 179 thereby connecting these passages to admit a full flow of compressed air to the operating cylinder 15.

The metering pin 221 is disposed in an opening 255 (Fig. 3) in the casting 177, which forms part of a bypass channel 257 connecting the passage 175 through an offset passage 259 to the passage 179. The metering pin 221 threadedly engages the opening 255 in the casting and is adjustable by rotating it in either direction to move the inner end thereof relative to the channel 257 to thereby regulate the flow of air through the bypass channel around the valve 223 and independently of the valve. A lock nut 261 is provided to lock the metering pin in its adjusted position.

35 Early in the upward movement of the valve 223 the groove 245 is moved out of alignment with the passages 175 and 179 thus blocking these passages. Thereafter, during the opening stroke of the piston 17, the air in the top of the cylinder 15 escapes to atmosphere through the bypass channel 175, 178, 182, 184 and the bypass channel 255, 257 and 259 under the control of the metering pin 221. The rate of flow of compressed air into circuit breaker operating cylinder through

40 45 50 55 60 the inlet passage 179, 257, 255 is adjusted by means of the metering screw 221 (Fig. 3) which controls the size of the passage through which air is admitted to the operating cylinder. This metering screw is adjusted to obtain the desired closing speed of the breaker. The size of the restricted inlet passage 255-257 is too small to permit high-speed venting of the compressed air trapped above the piston on opening operations. The size of the exhaust passage 178, 180, 182, 184 is such that rapid and full venting of the cylinder is obtained. The air back of the piston, however, is compressed sufficiently to cushion the final opening movement of the piston and the breaker mechanism.

65 70 75 When the closing magnet 197 (Fig. 2) is energized to initiate a closing movement of the operating mechanism, it closes the exhaust valve 193 (Fig. 2) and opens the inlet valve 185. This admits compressed air from the source (not shown) through the inlet chamber 186, inlet valve 185, passage 179, bypass channel 259, 257 and 255 (Fig. 3) and the passage 175 to the upper end of the operating cylinder 15 above the piston 17. This forces the piston downwardly and moves the connected operating mechanism toward closed position, the metering pin 221 acting to throttle the flow of air to the cylinder a predetermined amount. As the piston 17 (Fig. 2) moves downwardly in the cylinder, the lever 53 is rotated in a counterclockwise direction (Fig. 1)

and, at a predetermined time during this movement, the tappet 237 engages the upper end of the valve rod 227 and moves the valve 223 downwardly to its lower or open position in which the groove 245 is aligned with the passage 175-179. This occurs shortly before the breaker contacts engage, thus providing an increased volume of compressed air to bring the movable contacts quickly into pressure engagement with the stationary contacts.

The valve 223 is automatically controlled by the operating lever 53 according to the position of the breaker in such a manner that the valve will remain in its open position upon a quick automatic reclosing operation when the reclosing movement of the breaker is initiated when the breaker is in an intermediate or partially open position. This provides for the admission of a full volume of compressed air to the operating cylinder in order to quickly reverse the movement of the operating piston and breaker operating mechanism and to operate said mechanism to fully closed position.

From the foregoing it will be apparent that the valve mechanism provides for quick reversal of movement of the circuit breaker and piston and high-speed opening movement of these parts because of the rapid venting of the cylinder through the passage controlled by the exhaust valve 193. The throttle valve 223 together with the adjustable inlet passage 255-257 reduces the flow of compressed air admitted to the operating cylinder during the first part of the closing stroke on normal closing operations to prevent slamming of the parts but permits the full flow of compressed air to the cylinder during the final heavy load of the closing stroke.

While the invention has been disclosed in accordance with the provisions of the patent statutes, it is to be understood that various changes in the structural details and arrangement of parts thereof may be made without departing from some of the essential features of the invention. It is desired, therefore, that the language of the appended claims be given the broadest reasonable construction permitted in the light of the prior art.

I claim as my invention:

1. In a circuit interrupter having relatively movable contacts, operating means therefor comprising a cylinder, an operating piston in said cylinder operatively related with said circuit interrupter, a source of compressing gas, a control valve device associated with said cylinder for admitting compressed gas to said cylinder for operating said piston in one direction and for rapidly venting said cylinder directly to atmosphere to permit high-speed reverse movement of said piston, said valve device having an inlet passage connected to said cylinder, an exhaust passage communicating with the cylinder independently of said inlet passage for rapidly venting said cylinder directly to atmosphere, an inlet valve biased to normally close said inlet passage, an exhaust valve biased to normally open said exhaust passage, actuating means for said valves comprising an electromagnet operable to move said inlet valve to open position and to move said exhaust valve to closed position, a control valve disposed in said inlet passage between said inlet valve and said cylinder, said control valve being operable by the breaker mechanism to reduce the amount of compressed gas admitted to said cylinder to effect closing of said interrupter from a full open position, adjusting means for varying

at will the minimum amount of compressed gas admitted to the cylinder to close the breaker from full open position and said control valve being operable during the closing movement to increase the amount of compressed gas admitted to the cylinder near the end of the closing movement of the interrupter.

2. An operating mechanism of the pneumatic type for operating an electrical circuit interrupter comprising a cylinder, a piston movable in said cylinder and operatively related with the circuit interrupter, a source of compressed gas, a control valve device for admitting compressed gas to said cylinder to move said piston in one direction to operate said interrupter and for also rapidly venting said cylinder directly to atmosphere, said valve device having an inlet passage communicating with said cylinder, a control valve disposed in said inlet passage, said control valve being operable to reduce the amount of compressed gas admitted to said cylinder to effect closing of the interrupter from full open position, means operable during the opening stroke for operating said control valve to admit a full flow of compressed gas to said cylinder near the end of the closing operation, a bypass channel around said automatic valve for rapidly venting said cylinder to atmosphere independently of said control valve, an inlet valve biased to a closed position to close off said inlet valve from said source, an exhaust valve biased to open said exhaust passage, and actuating means operable when energized to close the exhaust valve and open said inlet valve.

3. An operating mechanism for an electrical circuit interrupter comprising a cylinder, an operating piston in said cylinder for operating said interrupter, a source of compressed gas, a control valve device for admitting compressed gas to said cylinder to move the piston in one direction to operate said interrupter and for rapidly venting said cylinder directly to atmosphere to permit high-speed reverse movement of said piston, said valve device having an inlet passage connected to said cylinder, an exhaust passage for rapidly venting said cylinder directly to atmosphere independently of said inlet passage, valve means associated with said passages having a normal position closing said inlet passage and opening said exhaust passage, spring means biasing said valve means to said normal position, actuating means operable when energized to move said valve means to open said inlet passage and close said exhaust passage, a control valve disposed in said inlet passage automatically operable when said interrupter moves to open position to reduce the amount of compressed gas admitted to said cylinder, and means comprising a bypass channel around said control valve for admitting a predetermined amount of compressed gas independently of said control valve to effect normal closing operation from full open position said control valve being operable to admit a full flow of compressed gas near the end of the closing operation and also to admit a full flow of compressed gas to effect high-speed reverse movement of said piston.

4. An operating mechanism for an electrical circuit interrupter comprising a cylinder, an operating piston movable in said cylinder for operating said interrupter, a source of fluid under pressure, control valve means for admitting fluid pressure to said cylinder and for quickly venting said cylinder to atmosphere, said valve means having an inlet passage, an inlet valve, means

normally biasing said inlet valve to close said inlet passage, an electromagnet operable when energized to operate said inlet valve to open said inlet passage, a control valve disposed in said inlet passage and operable upon opening movement of said interrupter to reduce the amount of fluid pressure admitted to said cylinder on normal closing operations, adjustable means associated with said inlet passage to vary the rate of flow of the fluid pressure admitted to said cylinder, an exhaust passage bypassing said control valve, an exhaust valve biased to open said exhaust passage for rapidly venting said cylinder to atmosphere independently of said control valve, said exhaust valve being operable by said electromagnet to close said exhaust passage, and means for operating said control valve to cause a full flow of compressed fluid to be admitted to said cylinder during the latter portion of the closing movement of the interrupter.

5. An operating mechanism for a circuit interrupter comprising a fluid motor operable to close said interrupter, an inlet valve disposed in an inlet passage and operable to admit fluid pressure to said motor to effect closing of said interrupter, a control valve disposed in said inlet passage and operable at a predetermined time during an opening movement of said interrupter to substantially close said inlet passage, means comprising an auxiliary inlet passage for admitting fluid pressure at a predetermined rate to said motor to effect closing of the interrupter from full open position, an exhaust passage bypassing said inlet passages for rapidly venting said cylinder to atmosphere, an exhaust valve biased to open said exhaust passage, means operable to close said exhaust valve and open said inlet valve, and means operable during the closing operation for opening said control valve to cause greater fluid pressure to be applied to the motor near the end of the closing operation than at the beginning of the closing operation.

6. In an operating mechanism for a circuit breaker, an operating cylinder, a piston in said cylinder for moving said breaker to closed position, an inlet passage connecting said cylinder to a source of compressed gas, an exhaust passage connecting said cylinder to atmosphere, inlet and exhaust valves associated with said passages, means biasing said valves to normally open said exhaust passage and to close said inlet passage, electroresponsive means for simultaneously operating said valves to close said exhaust passage and open said inlet passage to thereby effect closing of said breaker, a control valve disposed in said inlet passage and operable to close said passage at a predetermined intermediate point in the opening movement of the breaker, means comprising a channel bypassing said control valve for admitting independently of said control valve a predetermined amount of compressed gas to the cylinder to close the breaker, adjustable means disposed in said bypass channel for adjustably determining the amount of compressed gas to be admitted to said cylinder to initiate closing movement of the breaker, and means operable during the closing movement of the breaker to cause opening of said control valve to thereby increase the amount of compressed air admitted to the cylinder at a predetermined intermediate point in the closing movement of the breaker.

7. An operating mechanism for a circuit breaker comprising a cylinder and a piston mov-

able therein for moving said breaker to closed position, a trip device operable to cause opening of the breaker, an inlet valve biased closed and operable to admit compressed air to said cylinder to close said breaker, an inlet passage connecting said inlet valve and said cylinder, a control valve disposed in said inlet passage between said inlet valve and said cylinder and operable to close said inlet passage at a predetermined intermediate point in the opening movement of the breaker, an exhaust passage bypassing said inlet passage and said control valve for rapidly venting said cylinder directly to atmosphere independently of said control valve, an exhaust valve biased to open said exhaust passage, actuating means operable when energized to close said exhaust valve and open said inlet valve, and means operable by a closing movement of said breaker to open said control valve to thereby admit a full flow of compressed gas to said cylinder near the end of the closing stroke.

8. In an electrical circuit breaker having movable contact means, operating means for said breaker comprising spring means biasing said breaker to open position, latching means for holding said circuit breaker closed, an operating cylinder, an operating piston in said cylinder non-releasably connected to the movable contact means for closing the circuit breaker, a source of compressed gas, a control valve device associated with said cylinder for admitting compressed gas to said cylinder for actuating said piston to close the breaker and for also rapidly venting said cylinder directly to atmosphere to permit high-speed opening of the circuit breaker, said control valve device having an inlet passage connected to said cylinder, an exhaust passage bypassing said inlet passage for rapidly venting said cylinder directly to atmosphere connected to said cylinder, an inlet valve biased to closed position to close said inlet passage, an exhaust valve biased to open said exhaust passage, spring means biasing said inlet valve closed and said exhaust valve open, valve actuating means comprising an electromagnet operable when energized for closing said exhaust valve and opening said inlet valve to admit compressed gas to said cylinder, a control valve disposed in said inlet passage intermediate said inlet valve and said cylinder for controlling the amount of compressed gas admitted to said cylinder and an auxiliary inlet passage bypassing said control valve for admitting a predetermined amount of compressed gas irrespective of said control valve.

9. In an electrical circuit breaker having movable contact means, operating means for said breaker comprising spring means biasing said breaker to open position, latching means for holding said circuit breaker closed, an operating cylinder, an operating piston in said cylinder non-releasably connected to the movable contact means for closing the circuit breaker, a source of compressed gas, a control valve device associated with said cylinder for admitting compressed gas to said cylinder for actuating said piston to close the breaker and for also rapidly venting said cylinder directly to atmosphere to permit high-speed opening of the circuit breaker, said control valve device having an inlet passage connected to said cylinder, an exhaust passage independent of said inlet passage for rapidly venting said cylinder directly to atmosphere connected to said cylinder, an inlet valve biased to closed position to close said inlet passage, an exhaust valve biased to open said exhaust passage, spring means

biasing said inlet valve closed and said exhaust valve open, valve actuating means comprising an electromagnet operable when energized for closing said exhaust valve and opening said inlet valve to admit compressed gas to said cylinder, a control valve disposed in said inlet passage intermediate said inlet valve and said cylinder for controlling the amount of compressed gas admitted to said cylinder, said control valve being operable to reduce the amount of compressed gas admitted to the cylinder on normal closing operations and to increase the amount of compressed gas admitted to the cylinder near the end of the closing movement and means for adjustably determining the minimum amount of compressed gas admitted to the cylinder on normal closing operations.

10. An operating mechanism for a circuit breaker comprising a cylinder, an operating piston in said cylinder for operating said circuit breaker, a source of compressed gas, an inlet passage communicating with said cylinder, an exhaust passage for rapidly venting said cylinder directly to atmosphere, an inlet valve biased to closed position to close said inlet passage, an exhaust valve biased to open said exhaust pas-

5 sage, actuating means operable when energized to close said exhaust valve and open said inlet valve, a normally open control valve disposed in said inlet passage biased to closed position and automatically operable upon movement of said breaker to open position to substantially close said inlet passage, an auxiliary inlet passage bypassing said control valve for admitting a predetermined amount of compressed gas to the cylinder independently of said control valve to effect closing of the breaker from full open position, and means operable during a closing movement of the breaker to open said control valve to thereby increase the flow of compressed gas to the cylinder near the end of the closing stroke.
